UNITED STATES PATENT OFFICE

151,280

DESIGN FOR A RAILWAY CAR DOOR OPENER AND CLOSER

Glenn W. Merritt, Bowerston, Ohio, assignor to
The Nolan Company, Bowerston, Ohio, a corporation of Ohio

Application March 11, 1946, Serial No. 127,333

Term of patent 14 years

(Cl. D50—5)

To all whom it may concern:

Be it known that I, Glenn W. Merritt, a citizen of the United States, residing at Bowerston, in the county of Harrison and State of Ohio, have invented a new, original, and ornamental Design for a Railway Car Door Opener and Closer, of which the following is a specification, reference being had to the accompanying drawing, forming a part thereof.

Fig. 1 is a top plan view of a railway car door opener and closer, showing my new design;

Fig. 2 is a front elevational view thereof.

Fig. 3 is an end elevational view; and

Fig. 4 is an elevational view looking toward the opposite end of the railway car door opener.

The rear side of the railway car door opener is identical to the front side as shown in Fig. 2.

I claim:

The ornamental design for a railway car door opener and closer, as shown and described.

GLENN W. MERRITT.
